Patented Oct. 12, 1971

222,295

SUNGLASS FRAME FRONT

Roger L. McCracken, Chili, N.Y., assignor to
Bausch & Lomb Incorporated, Rochester, N.Y.

Filed Mar. 30, 1970, Ser. No. 22,111

Term of patent 14 years

Int. Cl. D16—06

U.S. Cl. D57—1

FIG. 1

FIG. 2

FIG. 3

FIG. 4

FIG. 5

FIG. 6

FIG. 1 is a front view of a sunglass frame front showing my new design;

FIG. 2 is a perspective view thereof;

FIG. 3 is a side elevational view thereof as seen from the right of FIG. 1;

FIG. 4 is a front view of a second embodiment of my new design;

FIG. 5 is a perspective view thereof; and

FIG. 6 is a side elevational view thereof as seen from the right of FIG. 4.

The sides not shown have substantially the same appearance as the sides respectively shown.

I claim:

The ornamental design for a sunglass frame front, substantially as shown and described.
